18 Claims. (Cl. 122—478)

This invention relates to a fluid heating apparatus and more particularly to an improved construction and operation of a water tube steam boiler including a novel superheater arrangement which is particularly adapted for use in a marine installation.

As the trend in marine installations is toward higher optimum superheat steam temperature, it has been noted that in connection with the generation of high pressure and temperature steam in marine boilers fired by residual oil type fuels, serious difficulties have been encountered in maintaining metal temperatures of the superheater parts below the high temperature corrosion limits thereof, i.e. the temperature at which corrosion becomes excessive, when the same are customarily subjected to the high temperature combustion gases for producing desired relatively very high temperature superheat steam. It has been discovered that the corrosive impurities present in the residual fuel oils fired react with the metal superheater parts if the metal temperatures exceed an optimum temperature of 1150° F. causing the same to rapidly deteriorate or corrode, and thereby greatly reducing the effectiveness and useful life of the superheater parts. Consequently, for all practical purposes the superheat temperature of the steam generated is generally limited by the optimum high temperature corrosive limit, as above defined, of the superheater metal parts.

It is therefore the object of this invention to provide in an improved marine installation, a means whereby relatively very high superheat steam temperature may be produced while maintaining the metal temperatures of the superheater parts at or below their high temperature corrosion limit.

Heretofore, control superheat temperature over a wide range in a marine installation has been attained by means of a two-furnace, single uptake, control superheat boiler. As marine steam generating installations of this type are characterized by relatively low space and head room limitations, it is a necessary requisite that these units be compact and lightweight in design, yet capable of adequately high thermal efficiency requiring the minimum alteration of the surrounding ship structure. Because of the initial limitation of available installation space, units of this type were limited to the amount of steam superheating surfaces capable of being located therein in a position for effective heat absorption, the limited amount of superheater absorption surface being another factor which adversely affects the desirability of maximum superheat temperature with optimum permissible metal temperature of the superheater parts.

It is another object of this invention to provide in a marine boiler unit of a predeterminate weight and size, means for providing maximum superheater absorption surfaces without materially altering or enlarging the acceptable or allowable size and weight of the marine boiler which must of necessity be limited to the surrounding ship structure in which it is to be installed.

It is another object of this invention to provide an improved superheater arrangement capable of greater effec-

2

tiveness, yet is rendered readily accessible and easily maintained so that the same can be sustained over a relatively long period of time.

The above objects and advantages of the instant invention are attained by providing in a marine boiler burning residual fuel oils, an improved superheater construction comprising of at least a pair of superheater sections which are serially connected whereby each section thereof is disposed in adjacent progressively decreasing gas temperature zones of a gas convection pass. According to this invention, each section consists of a pair of vertical juxtaposed headers of which at least one is provided with means for partitioning the same into distinct chambers and a plurality of horizontally extending, nested U-shaped, superheater tubes connecting the chambers of one header in communication with its associated header. With this arrangement, each section is provided with a plurality of steam passes serially connected which are generally in counter and parallel heat transfer relationship to gas flow through the convection pass and which through any cross-sectional plan or section of the entire superheater is provided with a steam pass which is in both counter and parallel heat transfer relationship to the gas flow.

In one form of the invention, each section of the superheater is connected in series by a relatively large diameter crossover tube and in another form of the invention, each section is connected in series by a plurality of additional U-shaped superheater tubes.

With either of these arrangements, the relatively cool saturated steam accumulated in the steam drum is first introduced into that section of the superheater disposed in the hot portion of the gas convection zone. This relatively cool steam is then passed through the first section serially in several alternating passes which are generally in a counter and parallel heat transfer relationship to the gas flow whereby the steam is heated to an intermediate superheat steam temperature. The intermediate superheated steam is then introduced into the second or next succeeding superheater section which is disposed in the relatively cooler portion of the gas pass whereby the intermediate superheated steam is again successively or serially passed in several alternating passes which are generally in counter and parallel heat transfer relationship relative to the gas flow so as to become highly superheated thereby. In this manner, effective heat transfer is attained to produce the desired high temperature superheat steam while at the same time maintaining the tube temperatures of the various parts of the superheater below that temperature at which corrosion becomes excessive.

According to this invention, the superheater cavity is also extended to a maximum extent without materially increasing the weight and size of the boiler as determined by the surrounding ship's structure. This is attained by bounding the superheater cavity by a group of spaced screen tubes which are connected to a pair of spaced relatively small diameter water headers or drums rather than to a single relatively large water drum as was heretofore customary in a comparable boiler arrangement as shown in the patent to Rooney 2,332,534. With this novel arrangement, the superheater cavity may extend downwardly an amount sufficient to facilitate the addition of several more superheater tubes, thereby increasing the amount of available superheating surface over those of prior known construction having the same vertical height between upper drum and lower tube header.

This dual header arrangement is of further advantage in that by spacing the same, a hopper-like bottom is provided for the superheater cavity whereby the superheater tubes can be readily washed down and otherwise maintained, thereby facilitating cleaning of the superheater parts and consequently rendering the same more effective.

A feature of this invention resides in the provision of an improved superheater structure which is relatively simple in construction, easily maintained and positive in operation.

Another feature of this invention resides in the provision whereby an increase of superheater surface is attained without materially increasing the overall dimensions and weight of the boiler as determined by available installation space.

Still another feature of this invention resides in the provision whereby high optimum superheat steam temperatures are attainable while maintaining the metal temperature of the superheater parts within maximum trouble-free temperature limits.

A still further feature of this invention resides in the provision whereby the superheater parts can be readily cleaned and washed down as required.

Other features and advantages will be readily apparent when considered in view of the following description and drawings in which:

Fig. 8 is a perspective not to scale schematic view of the superheater arrangement of Fig. 6.

In the form of the invention illustrated in Figs. 1 to 3, the improved marine boiler of this invention consists of a setting 10 comprising of a front 11, rear 12, and side walls 13 and 14 which are substantially rectangularly disposed enclosing a main furnace cavity 15, an auxiliary furnace cavity 16 and a gas convection pass 17 associated with the latter and disposed between the auxiliary and main furnace cavities 15 and 16 respectively. Disposed between the side walls 13 and 14 and extending transversely across the upper portion of the setting, there is supported the steam and water drum 18. Laterally offset and disposed adjacent the lower portion of the side wall 13 is a water drum 19 which is connected to the steam drum 18 by a bank of inclined steam generating tubes 20 which extend longitudinally of the drums 18 and 19 and transversely across the setting. On the outer side of the generating tube bank 20, the side wall 13 connects to the front and rear wall to form a common flue 21 for exhausting the combustion gases of both furnaces, the gases of the auxiliary furnace 16 flowing through the convection pass 17 across the main furnace to the flue. Immediately adjacent the inner side of the tube bank 20 is located the main furnace cavity which is adapted to be fired by fuel burners 22. If desired, a heat trap in the form of economizer tubes and/or air heater tubes 23 are advantageously located in the flue 21.

The auxiliary furnace 16 is separated from the main furnace 15 by the associated gas convection pass 17. As shown the side 16a, roof 16b and rear wall 16c of the auxiliary furnace cavity are lined with water-cooled wall tubes. The side wall water tubes 24 extend vertically from the lower side wall header 25 and the extensions thereof are angularly inclined adjacent the roof to continue along the same to connect with the water and steam drum 18. The rear wall tubes 26 extend between the lower and upper rear wall headers 27 and 28 respectively, the latter being in communication with the steam drum 18 by means of riser tubes 28. Suitable fuel oil burners 29

34 located in the front wall independently fire the auxiliary furnace.

A distinctive feature of the instant invention resides in the provision of a pair of spaced relatively small water drums or headers 30 and 31 which extend transversely across the setting adjacent the bottom of the gas convection pass. Connecting each of the headers 30 and 31 to the steam and water drum 18 are a spaced group of water tubes 32 and 33 which extend transversely of the setting and form therebetween a superheater cavity, the tubes 32 and 33 forming a water cooled screen for protecting an improved superheater 35, as will be herein-after described, disposed within the cavity from excessive radiantly transmitted heat from high temperature gases in furnaces 15 and 16.

In the embodiment of Figs. 1 to 3, the screen tubes 32 extend upwardly from the water header 30 and incline slightly toward the main furnace 15, the lower half portion of the screen tubes 32 comprising a shield of bare, tangent touching tubes to protect the superheater 35 from flame radiation. Alternate tubes 32 at the upper half portion thereof are bent inwardly toward the superheater cavity to form spaces therebetween to provide passage openings for the combustion gases flowing through the gas convection pass. Screen tubes 33 are staggered. If desired, lower portions of tubes 33 may be studded and/or filled with refractory to form baffle means.

The water supply connections from drum 18 to the several steam or vapor generating sections of the unit include a plurality of downcomers disposed between the outer casing 36 and walls 11 and 12 of the setting 10. Referring to Figs. 1 and 2, drum 18 is connected to water drum 19 by downcomers 37. Downcomers 38 and 39 connect the drum 18 to the spaced water headers 30 and 31 respectively. Downcomer 40 connects the drum 18 to the rear wall header 27 and downcomer 41 connects the drum 18 to side wall header 25. The space formed by the walls 11 and 12 and casing 36 further provides a chamber through which combustion air is supplied to the burners 22 and 34.

According to this invention, the improved superheater arrangement 35 has its heat absorbing surfaces positioned in the gas convection pass 17 whereby said surfaces can be independently heated by the firing of the burners 34 associated with the auxiliary furnace cavity and thereby rendering superheat steam temperatures controllable over a relatively wide range. Since the trend in marine boilers is toward higher superheat steam temperatures, it has been discovered that because of the corrosive impurities present in the residual fuel oils, the superheater tubes rapidly corrode or deteriorate if heated to temperatures above 1150° F. Consequently for all practical purposes, the temperature of superheat steam obtainable is limited by that amount of heat which can be absorbed by the superheater metal parts which will not result in excessive corrosion thereof.

In this invention, the improved superheater arrangement 35 is designed to attain optimum superheat steam temperatures in the order of 1,000° F. or above while at the same time maintaining the temperature of the superheater metal parts within tolerable corrosion limits.

According to this invention, this is accomplished by a superheater arrangement which comprises a plurality of superheater sections which are connected in series, each section of the superheater having its heat absorption surfaces disposed in progressively decreasing gas temperature zones A and B of the gas convection pass 17. In the illustrated form of the invention, reference being had particularly to Figs. 3 and 7, the superheater 35 is shown as comprising an inlet section 42 to an outlet section 43. The inlet section 42 includes a pair of vertically disposed juxtaposed headers 45, 46 positioned between the casing 36 and adjacent the rear wall 12, one of the headers having connected thereto a steam inlet

pipe 44 connecting with the steam drum 18, and the outlet section consisting of juxtaposed headers 51 and 52, header 51 being provided with an outlet connection 58 for delivering the finally superheated steam to a point of use (not shown).

As shown, header 45 is divided by a diaphragm 47 which partitions header 45 into an upper inlet and a lower outlet chamber 48 and 49 respectively. Chambers 48 and 49 of header 45 are connected in communication with the associated header 46 by a plurality of nested, vertically spaced, U-shaped heat receiving superheater tubes 50. In the illustrated form of the invention of Fig. 3, the superheater tubes 50 are vertically stacked in nested groups of three, the vertically stacked tubes 50 being divided into an upper group 50A connecting the upper header chamber 48 to the associated intermediate header and a lower group 50B connecting the associated header 46 to the lower chamber 49 of header 45.

Referring to Fig. 7, it will be noted that the nested, vertically stacked tubes of group 50A each comprises an inlet leg portion 50A₁ extending horizontally across the convection pass, a cross-over portion 50A₂ forming a continuation thereof which extends beyond the front wall of the unit and a return leg 50A₃ which also extends across the convection pass upstream of the gas flow from that of the intake leg portion 50A₁. Each of the nested and vertically stacked group of tubes 50B likewise comprises an intake leg portion 50B₁ in communication with the interior of header 46 and which extends horizontally across the convection pass, a crossover portion 50B₂ forming a continuation of leg 50B₁ extending through the front refractory wall and return leg portion 50B₃ spaced downstream of intake leg portion 50B₁, leg 50B₃ being in communication with chamber 49. In Figs. 3 and 7, it will be noted by the broken arrow indicating the steam flow that the saturated steam from the steam drum is introduced into header 45 through inlet 44 and flows through the inlet section 42 in the following manner. The steam introduced into header 45 flows into chamber 48, then through the intake leg portion 50A₁ of nested tube group 50A, through the cross-over portion 50A₂ and through the return leg portion 50A₃ wherein the steam is discharged into the associate header 46 in a steam flow path which is generally in a counterflow, heat transfer relationship to that of the gas flow. The combined delivery of steam from all of the tubes 50A then moves down the associate header 46 and into the lower group of superheater tubes 50B whereby the steam is directed from header 46 through the intake leg portion 50B₁, through the cross-over portion 50B₂, thence through the return leg portion 50B₃ and finally into lower chamber 49 of header 45, traversing a steam flow path which is generally in a parallel flow heat transfer relationship to that of the gas flow. By this arrangement, it is possible for the saturated steam to be superheated to an intermediate temperature in which state it is directed from chamber 49 through the large diameter cross-over pipe 57 to the outlet section.

The outlet section 43 comprises header 51 having an outlet connection 58 and an associated intermediate header 52, the header 51 being divided by a diaphragm 53 into upper and lower chambers 54 and 55 respectively. Vertical stacks of nested U-shape heat absorbing tubes 56 connect the chambers 54 and 55, header 51 to its associated header, the stack of tubes 56 being divided into a lower portion 56A connecting the lower chamber 55 to the associated header 52 and an upper group 56B connecting the associated header 52 to the upper chamber 54.

Referring to Fig. 7, each of the nested tubes vertically stacked in group 56A comprises an intake leg portion 56A₁ communicating with chamber 55 and extending across zone B of the convection pass, a cross-over portion 56A₂ forming a continuation of leg 56A₁ which extends through the front refractory wall 11 and a return

leg portion 56A₃ spaced upstream of the intake leg portion 56A₁ with respect to the gas flow, the return leg portion 56A₃ being in communication with the interior of the associated intermediate header 52. Thus, it will be noted that the intermediate superheated steam introduced into chamber 55 through the cross-over tube 57 flows through the intake leg portions 56A₁ of the tube group 50A through the cross-over portion 56A₂ and thence through the return leg portion 56A₃ wherein the steam is discharged into the associated header 52, the steam traversing a flow path through tubes 56A which is generally in a counterflow heat transfer relationship to that of the gas flow in the convection pass. The combined delivery of the steam from all of the tubes 56A then moves up the associated header 52 and flows outwardly therefrom through the intake leg portion 56B₁ through the cross-over portion 56B₂ forming a continuation thereof and thence through the return leg portion 56B₃ spaced downstream of leg portion 56B₁ with respect to gas flow wherein the steam is finally discharged into the upper chamber 54 of header 51, the steam traversing a flow path through tubes 56B which is generally in a parallel heat transfer relationship to that of the gas flow. Thus, it will be noted that the intermediate superheat steam flowing through the outlet section 43 of the superheater is raised to its finally superheated steam temperature in which state it is delivered through the outlet pipe 58 at its optimum superheated temperature to a point of use.

By this arrangement, it will be noted that the relative cool steam at saturated temperature is first introduced into section 42 of the superheater, the heat absorption surfaces of which are exposed to the hottest gas in zone A in the gas convection pass, and that by flowing the steam serially in several alternating counter and parallel flow heat transfer relationships between header 45 and 46 in the hot zone, the saturated steam is superheated to an intermediate temperature whereby the relative steam temperatures within the tubes 50 and the gas temperature heating the surfaces thereof are such that the superheater metal temperatures are maintained below their high temperature corrosive limit. The intermediate superheated steam is then passed into the second section of the superheater, disposed in the cooler zone B and the steam finally heated therein by means of flowing the steam in through the second superheater section in generally an alternate counter and parallel heat transfer relationship to the gas flow. Thus, a highly heated superheat steam is attained in that portion of the superheater having its metal heat absorption surfaces exposed to the relatively cooler combustion gases of zone B. In this manner, a more uniform balance is achieved between the relative temperatures of the steam, the combustion gases and the associated metal superheater parts in contact therewith. Consequently, this balance is maintained so that the optimum superheat steam temperatures of 1000° F. or above may be achieved without the metal parts of the superheater parts exceeding temperatures at which intolerable corrosion of the superheater tubes 50 and 56 occurs.

According to this invention, it will be noted that the utilization of the spaced water header construction 30 and 31 as hereinbefore described enables the superheater cavity or section to be extended downwardly a maximum extent. This is rendered possible over the prior-known construction because it has been discovered that by utilizing a pair of spaced smaller diameter water headers 30 and 31, the tube groups 32, 33 connecting into each of the water headers 30 and 31 respectively may extend downwardly a greater amount before the lower ends thereof 32a, 33a are bent for connecting the same into its respective header. For this reason, additional space is availed of without altering the overall size of the unit wherein several additional superheater tubes 50 and 56 may be accommodated and thereby in-

creasing the overall amount of heat absorbing surface of the superheater. Thus it will be noted that for a given steam temperature with the greater the amount of superheater absorption surface available, lower resultant tube temperatures are attained and conversely, for any given tube temperature, the more superheater absorption surface available, the higher will be the superheat steam temperature.

It is to be further noted in the instant invention that the superheater cavity is provided with a hopper-like bottom 59 between the water headers 30 and 31, the bottom of the cavity consisting of an inclined refractory floor terminating in the centrally disposed opening 60 which is adapted to be closed by a removable closure 61. Because of this construction, the superheater tubes 50 and 56 may be readily washed down or otherwise maintained so that they can be kept comparatively clean thereby increasing the efficiency thereof. As shown in Fig. 2, the U-shaped, vertically stacked superheater tubes 50 and 56, nested in groups of three are rendered readily accessible in that the space between the horizontally extending leg portions of the U-shaped tubes of each section 42, 43 provide sufficient walk-in area so that an operator may physically enter and physically clean tubes by hose and/or scraping or the like to maintain the tubes reasonably clean for sustaining the effectiveness of the same. Thus, the instant superheater arrangement herein described allows for optimum superheat steam temperatures while maintaining the metal temperatures thereof within safe operating limits and also the arrangement thereof is such that greater accessibility and ease of maintenance may be had without increasing or altering substantially the overall size and dimensions of the unit.

It will be further noted that the tubes 50 and 56 extend through the front and rear walls and are supported thereby. If desired, a plurality of large diameter water tubes 62 connecting the drum 18 to headers 30 and 31 are disposed in pairs adjacent tubes 50 and 56 for supporting the intermediate portion of the horizontal legs of the nested tubes, each pair of tubes having secured thereto suitable superheater supporting plates 63.

A modified form of the invention is illustrated in Figs. 4 to 8. In this form of the invention the marine boiler unit is arranged generally in much the same manner as hereinbefore described, but utilizing a modified superheater arrangement. As shown the setting 110 comprises a front wall 111, rear wall 112, and side walls 113 and 114 which are rectangularly disposed and enclose a main furnace cavity 115, an auxiliary furnace cavity 116 and a gas convection pass 117 disposed therebetween, each of the furnace cavities 115 and 116 being independently fired by fuel burner means 118 and 119. The water and steam drum 120 is supported adjacent the upper portion of the unit and extends transversely of the setting in the vicinity of the gas pass. Laterally offset and adjacent the bottom portion of the side wall 113, there is positioned a water drum 121 which is connected to the steam drum 120 by a bank of inclined generating tubes 122. As hereinbefore described, on the outer side of the tube bank 122 the unit is provided with a common flue 123 for exhausting the gases of both furnaces. A heat trap, e.g. air heater and/or economizer tubes 124 as shown may be advantageously located in the flue. Immediately adjacent the inner side of the tube bank 122 is disposed the main furnace cavity 115.

To the left of the gas convection pass 117 as viewed in Fig. 4 is located the auxiliary furnace cavity 116 which is fired by burners 119.

The auxiliary furnace 116 in this form of the invention is likewise provided with water cooled side walls 116a, rear wall 116b, and roof 116c, the side wall tubes 125 extending vertically from the lower side wall header 126 and inclining adjacent the roof of the furnace to continue therewith to connect into the water and steam drum 120. The rear furnace wall tubes 127 extend be-

tween the lower 128 and the upper 129 rear wall headers, the latter being connected to the main steam drum 120 by riser tubes 130.

Positioned below the main water and steam drum 120 are a pair of spaced relatively small diameter water headers 131 and 132 which extend transversely across the setting at the bottom of the gas convection pass 117, each of the water headers 131 and 132 being connected to the steam drum 120 by a group of spaced water tubes 133 and 134 respectively which extend transversely across the setting and form therebetween a superheater cavity. As hereinbefore described, the spaced group of tubes 133, 134 form a water cooled screen for protecting the modified superheater 135 in the superheater cavity from flame radiation.

As shown in Fig. 4, the screen tubes 133 extend upwardly from the water drum 131, the lower portion of the screen consisting of bare, tangent touching tubes to form an imperforate shield, while the upper portion of the screen has alternate tubes inclined outwardly to provide spaces therebetween for permitting the gases to flow out from the gas pass and into the upper portion of the main furnace from whence they are exhausted through the flue 123. Screen tubes 134 are alternately staggered throughout the greater portion thereof. Thus, it will be noted that when the burners of the auxiliary furnace are fired, the combustion gases tend to flow from the auxiliary furnace through screen tubes 134 and into the gas convection pass 117 whereby the gases are directed over the superheater after which the gas flows outwardly through the passages formed between tubes 133 at the upper portion of the screen.

The water supply connection from the drum 120 to the various drums and headers of the unit include a plurality of downcomers which are disposed in the spaces formed between the outer casing 136 and the front and rear wall of the setting. Referring to Fig. 5 downcomers 137 connect the drum 120 to the water drum 121 and downcomers 138 and 139 connect the steam drum 40 to the spaced water header 131 and 132 respectively while downcomers 140 connect the steam drum 120 to the side wall header 126 and downcomer 141 connects the steam drum to the rear wall header 128.

The modified superheater arrangement 135 as illustrated in the embodiment of Figs. 4 to 6 and 8 comprises an inlet section 142 and an outlet section 143. As shown in Fig. 6, the inlet section 142 includes an inlet header 144 and a juxtaposed associated header 145 vertically disposed between the casing 136 and the rear wall 112, each header being provided with a diaphragm means 146, 147, respectively for partitioning each into an upper and lower chamber. As shown in Figs. 6 and 8 it will be noted that the diaphragm 146, 147, dividing their respective headers into upper and lower chambers, are located at different elevations whereby the inlet header 144 is divided into an upper chamber 148 and a relatively shorter lower chamber 149 while the associated header 145 is divided so as to have substantially equal lower and upper chambers 150 and 151 respectively which are approximately double the length of the lower inlet header chamber 149.

A group of horizontally, vertically stacked, nested, hairpin tubes 152 extending through the rear wall and across the hot zone of the gas pass connect the chambers 148 and 149 of the inlet header 144 with the chambers 150 and 151 of the header 145. As indicated in Fig. 6, the vertically stacked, hairpin tubes 152 are divided into an upper portion 152a, an intermediate portion 152b, and a lower portion 152c. The lower portion 152c of the tubes 152 connects the lower chamber 149 of the inlet header 144 to the lower half of chamber 150, the intermediate group 152b connects the upper half of chamber 150 of the associated header 145 with the lower portion of the upper inlet header chamber 148 and the upper group of tubes 152a connects the upper portion of the

chamber 148 to the upper chamber 151 of the associated header 145. Thus, the steam flows through the inlet section 142 in several passes which are in alternately parallel and counter flow heat transfer relationship to that of the gas pass flowing through the convection pass. In the illustrated form, the upper portion 152a of the hairpin tubes are nested in pairs while the intermediate and lower portions 152b and 152c respectively are nested in groups of threes.

The outlet section 143 includes an outlet header 153 and a juxtaposed associated header 154 vertically disposed between the casing 136 and the rear wall and spaced from inlet section 142. The headers 153 and 154 of the outlet section 143 are likewise partitioned by means of diaphragms 155, 156 wherein the diaphragm divides the outlet header 153 into upper and lower chambers 157, 158, respectively, which are substantially equal and correspond in length to the respective chambers 148 and 149 of the inlet header 144 and the associated header 154 is divided into upper and lower chambers 159-160 substantially similar to that of the associated header 145 of the inlet section.

A group of horizontally extending vertically stacked hairpin tubes 161 extending through the rear wall 112 and extending across the cooler portion gas pass connects the chambers 157, 158 of the outlet header 153 with the chambers 159, 160 of the associated header 154, the vertical stack of tubes 161 being divided into an upper 161a, intermediate 161b and lower 161c portions. Referring to Figs. 6 and 8, it will be noted that the upper portion 161a of the tubes 161 connects the upper chamber 159 of associate header 154 to the upper portion of the upper chamber 157 of the outlet header. The intermediate portion 161b of the tubes connects the lower portion of the upper chamber 157 in communication with the upper portion of the lower chamber 160 of the associated header 154 and the bottom portion 161c of the tubes connect the lower portion of the lower chamber 160 in communication with the lower chamber 158 of the outlet header 153. Thus it will be noted that the steam flows through the superheater outlet section 143 in a plurality of passes in alternating parallel and countersteam flow heat transfer relationship relative to the gas flow through the convection pass.

According to this form of the invention, the superheater inlet section 142 and outlet section 143 are connected in series by means of a plurality of horizontally extending, vertically stacked, nested pairs of U-shaped, crossover tubes 162 which extend across the convection gas pass, the U-tubes connecting the upper chamber 151 of the header 145 to the upper chamber 159 of the header 154. In addition to the functioning as cross-over tubes, the group of U-shaped tubes 162 also increase the amount available of heat absorption surfaces of the superheater. It will be further noted that the vertically arranged tubes 161 of the outlet section are nested in pairs. Thus the velocity of the superheat steam in the outlet section is increased thereby functioning as an aid to maintain lower tube temperatures in that portion of the superheater in which the higher steam temperatures are attained.

In the modified form of the superheater, relatively cool saturated steam is introduced into the inlet section 142 which is disposed in the hot zone A' of the convection pass 117 through pipe 163. Flowing the steam back and forth between the headers 144 and 145 of the inlet section through tubes 152 in alternate passes of parallel and counter flow heat transfer relationship, as indicated by the arrows, the saturated steam is effectively superheated to an intermediate temperature. The intermediate superheat steam is then directed into the outlet section 142 through the cross-over superheater tubes 162, whereby the steam is finally superheated to maximum temperatures by passing the same through a series of parallel and counter-flow heat transfer relationship between headers 153 and 154 through tubes 161, the latter

being disposed in the cooler portion B' of the gas pass. Thus, the arrangement is such that the hottest steam temperature is attained in that portion of the superheater disposed in the coolest portion of the gas convection pass, the arrangement being such that maximum steam temperatures are attained while maintaining tube temperature below their high temperature corrosive limit. The finally superheated steam is then discharged through pipe 164.

As hereinbefore described, two spaced water headers 131 and 132 enable the superheater cavity to extend downwardly a maximum extent. In addition, the construction further enables the superheater cavity to be provided with a hopper-like bottom 165 having an opening 166 disposed between the headers 131 and 132, the opening 166 being provided with a suitable closure 167. Thus, with this construction, maintaining and cleaning of the tubes is greatly facilitated as hereinbefore described.

In both forms of the invention illustrated, it will be noted that the superheater tubes 50, 56, 152, 161 and 162 extend through both the refractory front and rear walls and are supported thereby, thus, greatly facilitating and simplifying the fabrication and supporting means of the superheater tubes.

The operation of the boiler arrangements herein described is as follows:

The steam generating unit is started up with only the main furnace burners in use. The heating gases generated by the fuel burning in suspension in the main furnace flow transversely of the generating tube bank to the gas outlet flue, passing over the air heater and/or economizer tubes before leaving the unit, the water cooled screen tubes forming an effective radiant heat shield between the main furnace cavity and the superheater tubes. When sufficient steam is flowing through the superheater tubes, the auxiliary furnace burners are started up and are regulably operated as to number and firing rate to control the superheat steam temperatures.

The heating gases generated in the auxiliary furnace chambers flow substantially horizontally across the rows of screen tubes and superheater tubes throughout their length due to the gas flow equalization space formed by the arrangement of the screen tubes throughout its extent in space relation with the superheater tubes. This construction further facilitates effective convection heating of the entire superheating surface.

According to this invention the hottest gases generated in the auxiliary furnace cavity flow through the rows of staggered screen tubes 33, 134 and across the superheater tubes 50, 152, the latter thus being disposed in the hottest portion of the gas convection pass. Flowing the steam in a plurality of passes that are in substantial parallel and counter flow heat transfer to the gas flowing over tubes 50, 152 of the inlet section of the superheat, effectively superheats the steam therein to an intermediate temperature whereby hot combustion gas temperatures in contact therewith are proportionately cooled. Thus the tubes subjected to the hottest gases are in contact with relative low temperature steam.

The intermediate superheat steam is then directed to the outlet section of the superheater. The relatively cooler combustion gases flowing over sections 42, 142 are then brought into contact with the outlet section 43, 143 of the superheater wherein the intermediate superheat steam flowing through the outlet section in a plurality of passes of alternating counter and parallel flow heat transfer relative to the combustion gas flow becomes highly superheated therein. Thus, it will be noted that the tubes exposed to the higher steam temperature are externally in contact with the lower gas temperatures in the gas pass. Consequently the arrangement is such that the balance of relative temperatures attainable between the combustion gases, metal parts of the superheater and steam in contact therewith enables the attain-

11

ment of maximum temperature of superheat steam without exceeding safe operating superheater tube temperature.

After leaving the superheater tubes, the gases flow across the upper portion of screen tubes 32, 133 and through the passage opening thereof to the extreme upper portion of the main furnace cavity. The confinement of the auxiliary furnace products of combustion to the extreme upper portion of the main furnace cavity avoids the introduction of relatively cold and inert gases into the main combustion zone of the main furnace cavity so that combustion is completed therein with little or no interference by the heating gases of the auxiliary furnace. The gases are then passed across the upper end of the tube bank to the outlet flue within which they contact the economizer and/or air heater tubes. The contact of these gases with the bank of tubes and air heater or economizer tubes further reduces their temperatures to the desired value, thereby increasing the efficiency of the unit.

The fuel supply to the burners in either of the cavities can be regulated either manually or automatically to maintain any desired superheat temperatures over a relatively wide range. The described constructions are particularly advantageous in providing a heating gas flow path from the auxiliary furnace chamber which follows the natural flow path of the gases without any substantial change of direction of the same; consequently the pressure drop throughout is extremely low.

From the foregoing description it will be noted that the two furnace, single uptake type, marine boiler of the instant invention is provided with a superheater having more heat absorption area effectively disposed in a gas convection pass which is divided into progressively decreasing temperature zones wherein steam is effectively superheated in stages from a saturated steam temperature to an intermediate superheat temperature in the hot zone and from said intermediate temperature to a high optimum superheat temperature in the cooler zone. This is accomplished by flowing the steam in each zone in a plurality of alternating parallel and counter-flow steam heat transfer relationship relative to the gas flow through the convection pass. Thus the heating of the relatively cool saturated steam to an intermediate superheat temperature in the hot zone and highly superheating the intermediately heated superheat steam in the cooler zone as described provides the attainment of maximum superheat steam while maintaining superheater tube temperatures within their high temperature corrosion limit.

Further, the arrangement is such that superheater cavity is bottomed by a pair of space water headers to provide for the formation of a hopper bottom having a centrally disposed opening to facilitate maintenance, hosing and cleaning of the superheater tubes. Also the nesting of the superheater tubes into relative small groups further aids in rendering each tube individually accessible for cleaning.

While the instant invention is disclosed herein with particular references to specific embodiments thereof, it is to be appreciated that the invention is not to be taken as limited to all of the details thereof, as modifications and variations thereof may be made without departing from the spirit or scope of the invention.

What is claimed is:

1. In combination with a two furnace, single uptake, controlled superheat boiler, the improvement of a gas convection pass disposed between said furnaces, said pass having progressively decreasing gas temperature zones, a superheater arrangement having a plurality of sections serially connected and including a first section disposed in the hottest gas zone and each succeeding section being located in successive lower temperature zones of said gas pass, said sections each including a plurality of heat absorbing superheater tubes extending transversely of its respective temperature zone, means for introducing sat-

12

urated steam into said first section and means for serially flowing steam through each of said sections successively in a steam flow that is in an alternating counter and parallel flow heat transfer relationship to the gas flow whereby said steam is superheated in each section to successive increasing superheat temperature until said steam is superheated to an optimum high temperature, said high temperatures being readily available while said tube temperatures are maintained within tolerable corrosive temperature limits.

2. The invention as defined in claim 1 wherein a said steam flow through said superheater in a plan section thereof is in both counter and parallel flow heat transfer relationship to said gas flow.

3. In combination with a two furnace, single uptake, controlled superheat boiler, the improvement of a gas convection pass disposed between said furnaces, said pass having progressively decreasing gas temperature zones, a superheater arrangement including a first section and a second section serially connected, each section being located in succeeding temperature zones of said gas pass, said sections each including a plurality of heat absorbing superheater tubes extending transversely across its respective temperature zone and means for serially flowing steam through each of said sections in a steam flow that is in an alternating counter and parallel flow heat transfer relationship to the gas flow whereby said steam is superheated in each section to successive increasing superheat temperature until said steam is superheated to an optimum high temperature, said high temperatures being readily available while said tube temperatures are maintained within tolerable corrosive temperature limits.

20 4. In combination with a two furnace, single uptake, controlled superheat boiler, the improvement of a gas convection pass disposed between said furnaces, said pass having progressively decreasing gas temperature zones, a superheater arrangement including a first section and a second section serially connected, each section being located in succeeding temperature zones of said gas pass, said sections each including a plurality of heat absorbing superheater tubes extending transversely across its respective temperature zone and means for serially flowing steam through each of said sections in a steam flow that is in an alternating counter and parallel flow heat transfer relationship to the gas flow whereby said steam is superheated in each section to successive increasing superheat temperature until said steam is superheated to an optimum high temperature, said high temperatures being readily available while said tube temperatures are maintained within tolerable corrosive temperature limits.

25 5. In combination with a two furnace, single uptake, controlled superheat boiler, the improvement of a gas convection pass disposed between said furnaces, said pass having progressively decreasing gas temperature zones, a superheater arrangement including a first section and a second section serially connected, each section being located in succeeding temperature zones of said gas pass, said sections each including a plurality of heat absorbing superheater tubes extending transversely across its respective temperature zone and means for serially flowing steam through each of said sections in a steam flow that is in an alternating counter and parallel flow heat transfer relationship to the gas flow whereby said steam is superheated in each section to successive increasing superheat temperature until said steam is superheated to an optimum high temperature, said high temperatures being readily available while said tube temperatures are maintained within tolerable corrosive temperature limits.

30 6. In combination with a two furnace, single uptake, controlled superheat boiler, the improvement of a gas convection pass disposed between said furnaces, said pass having progressively decreasing gas temperature zones, a superheater arrangement including a first section and a second section serially connected, each section being located in succeeding temperature zones of said gas pass, said sections each including a plurality of heat absorbing superheater tubes extending transversely across its respective temperature zone and means for serially flowing steam through each of said sections in a steam flow that is in an alternating counter and parallel flow heat transfer relationship to the gas flow whereby said steam is superheated in each section to successive increasing superheat temperature until said steam is superheated to an optimum high temperature, said high temperatures being readily available while said tube temperatures are maintained within tolerable corrosive temperature limits.

35 7. In combination with a two furnace, single uptake, controlled superheat boiler, the improvement of a gas convection pass disposed between said furnaces, said pass having progressively decreasing gas temperature zones, a superheater arrangement including a first section, said first section having a plurality of heat absorbing superheater tubes extending transversely of said convection pass in the hottest zone thereof, means for serially flowing steam through said tubes in a plurality of passes in alternating counter and parallel flow heat transfer relationship to the gas flow whereby said steam is heated to an intermediate superheat temperature, a second section, means connecting said sections in series, said second section including a plurality of superheater tube members extending transversely of the convection pass in the next succeeding lower gas zone, and means for serially flowing said intermediately heated steams through said tube members in a plurality of passes

40 8. In combination with a two furnace, single uptake, controlled superheat boiler, the improvement of a gas convection pass disposed between said furnaces, said pass having progressively decreasing gas temperature zones, a superheater arrangement including a first section, said first section having a plurality of heat absorbing superheater tubes extending transversely of said convection pass in the hottest zone thereof, means for serially flowing steam through said tubes in a plurality of passes in alternating counter and parallel flow heat transfer relationship to the gas flow whereby said steam is heated to an intermediate superheat temperature, a second section, means connecting said sections in series, said second section including a plurality of superheater tube members extending transversely of the convection pass in the next succeeding lower gas zone, and means for serially flowing said intermediately heated steams through said tube members in a plurality of passes

45 9. In combination with a two furnace, single uptake, controlled superheat boiler, the improvement of a gas convection pass disposed between said furnaces, said pass having progressively decreasing gas temperature zones, a superheater arrangement including a first section, said first section having a plurality of heat absorbing superheater tubes extending transversely of said convection pass in the hottest zone thereof, means for serially flowing steam through said tubes in a plurality of passes in alternating counter and parallel flow heat transfer relationship to the gas flow whereby said steam is heated to an intermediate superheat temperature, a second section, means connecting said sections in series, said second section including a plurality of superheater tube members extending transversely of the convection pass in the next succeeding lower gas zone, and means for serially flowing said intermediately heated steams through said tube members in a plurality of passes

6. A marine boiler consisting of a setting, an upper steam and water drum, a laterally offset lower water drum, a bank of inclined steam generating tubes connecting said upper and lower drums, a pair of spaced water headers arranged below said upper drum, spaced groups of vertically arranged water tubes connecting the upper drum to each of said lower pair of water headers, said spaced groups of tubes forming therebetween a superheating cavity and said pair of spaced water headers cooperating to extend the superheater cavity to a maximum extent and to form a hopper bottom of said superheater cavity to facilitate cleaning of the same, a main furnace chamber between said tube bank and said tube group, means for firing said main furnace, a multi-steam flow superheater disposed in said superheating cavity and screened by said spaced group of water tubes for superheating steam to a relatively high temperature while maintaining said superheater temperature below its high temperature corrosion limit, an auxiliary furnace chamber laterally adjoining the outer side of said superheater tubes, means for independently firing said auxiliary furnace chamber, a single heating gas outlet flue at the outer side of said tube bank and arranged to receive all of the heating gases flowing from both of said furnace chambers, said flue being so located that the heating gases from said auxiliary furnace chamber tend to flow over said superheater, through the main furnace chamber and across said tube bank before entering said flue, said steam flow in said superheater being in alternating counter and parallel flow heat transfer relationship with respect to the gases flowing from said auxiliary furnace.

7. The invention as defined in claim 6 wherein the lower half of said groups of vertically arranged tubes disposed between the main furnace and said multi-pass superheater are contiguous tangent touching tubes to shield said superheater from flame radiation.

8. A marine boiler consisting of setting, an upper steam and water drum, a laterally offset lower water drum, a bank of inclined steam generating tubes connecting said upper and lower drums, a pair of spaced water headers arranged below said upper drum, a spaced group of vertically arranged water tubes connecting the upper drum to each of said lower pair of water headers, said spaced group of tubes forming therebetween a superheater cavity and said pair of spaced water headers cooperating to extend the superheater to a maximum extent and to form a hopper bottom for said superheater cavity to facilitate cleaning of the same, a main furnace chamber between said tube bank and said tube group, means for firing said main furnace, a series multipass-superheater disposed in said superheating cavity and screened by said spaced group of water tubes, an auxiliary furnace chamber laterally adjoining the outer side of said superheater tubes, means for independently firing said auxiliary furnace chamber and a single heating gas outlet flue at the outer side of said tube bank and arranged to receive all of the heating gases flowing from both of said furnace chambers, said flue being so located that the heating gases from said auxiliary furnace chamber tend to flow over said superheater, through the main furnace chamber and across said tube bank before entering said flue, said steam flow in said superheater being in alternating counter and parallel flow heat transfer relationship with respect to the gases flowing from said auxiliary furnace.

9. A marine boiler consisting of setting; an upper steam and water drum; a laterally offset lower water drum; a bank of inclined steam generating tubes connecting said upper and lower drums; a pair of spaced water headers arranged below said upper drum; a spaced group of vertically arranged water tubes connecting the upper drum to each of said lower pair of water headers, said spaced group of tubes forming therebetween a superheater cavity and said pair of spaced water headers cooperating to form a hopper-bottom for said superheater

cavity to facilitate cleaning the same; a main furnace chamber between said tube bank and said tube group; means for firing said main furnace; a superheater including a pair of vertical, juxtaposed headers, one of said headers having a diaphragm means dividing the same into a plurality of chambers and plurality of vertically stacked, horizontally extending U-shaped tubes connecting chambers of said latter header to said other header for establishing a criss-crossing steam flow path between said headers, said U-shape tubes being disposed in said superheater cavity and screened by said spaced group of water tubes; an auxiliary furnace chamber laterally adjoining the outer side of said superheater tubes; means for independently firing said auxiliary furnace chamber; a single heating gas outlet flue at the outer side of said tube bank and arranged to receive all of the heating gases flowing from both of said furnace chambers, said flue being so located that the heating gases from said auxiliary furnace chamber tend to flow over said superheater in alternating parallel and counter flow heat transfer relationship to the steam flow through said superheater, thence through the main furnace chamber and across said tube bank before entering said flue.

10. A marine boiler comprising of a setting having a main furnace cavity; an auxiliary furnace cavity; a gas convection pass associated with said auxiliary furnace cavity and disposed between said furnace cavities, said convection pass including a hot gas zone and a relatively cooler gas zone; means for independently firing each of said furnace cavities; an upper steam and water drum; a laterally offset lower water drum; a bank of inclined steam generating tubes connecting said upper and lower drums; a pair of spaced water headers arranged below said upper drum; a spaced group of vertically arranged water tubes connecting the upper drum to each of said lower pair of water headers, said spaced group of tubes forming therebetween a superheater cavity, said pair of spaced water headers enabling said superheater cavity to be extended a maximum extent and said spaced water headers cooperating to form a hopper-bottom for said superheater cavity to facilitate cleaning of the same, said main furnace being disposed between said tube bank and said tube group; a superheater including a first section and a second section, said first section having a first pair of vertically disposed headers consisting of an inlet header and an associated header, said inlet header having a diaphragm means dividing the same into a plurality of chambers, a plurality of U-shaped horizontally extending tubes connecting said chambers of said inlet header with said associated header for establishing a steam flow path between said first pair of headers having a portion which is generally in counter flow heat transfer relationship to said gas flow and a second serially connected portion which is generally in a parallel heat transfer relationship to the gas flow, said U-shaped tubes being disposed in the hot zone of said superheater cavity whereby said steam flowing therethrough is superheated to an intermediate temperature; said second section including a second pair of vertically disposed headers including an outlet header and an associated header, said outlet header having a diaphragm means dividing the same into a plurality of chambers, a plurality of U-shaped, horizontally extending tubes connecting said chambers of said outlet header to said associated header for establishing a steam flow path between said second pair of headers having a portion which is generally in counter flow heat transfer relationship to said gas flow and a second serially connected portion which is generally in a parallel heat transfer relationship to the gas flow, said latter U-shaped tubes being disposed in said cooler zone of said superheater cavity and a tube means connecting said sections so that the steam flows from said first superheater section to said second section whereby the intermediate superheated steam generated in said first section is highly heated in said second section; said auxiliary furnace being disposed

adjoining the hot zone of said superheater cavity so that the heating gases from said auxiliary furnace tend to flow relative to the steam flow in the superheater whereby said steam is superheated to a relatively high temperature while the superheater tube temperatures are maintained below their high temperature corrosion limit.

11. A marine boiler comprising of a setting having a main furnace cavity; an auxiliary furnace cavity; a gas convection pass associated with said auxiliary furnace cavity and disposed between said furnace cavities, said convection pass including a hot gas zone and a relatively cooler gas zone; means for independently firing each of said furnace cavities; an upper steam and water drum; a laterally offset lower water drum; a bank of inclined steam generating tubes connecting said upper and lower drums; a pair of smaller spaced water headers arranged below said upper drum; a spaced group of vertically arranged water tubes connecting the upper drum to each of said lower pair of water headers, said spaced group of tubes forming therebetween a superheater cavity, said pair of spaced water headers enabling said superheater cavity to be extended to a maximum extent and said spaced water headers cooperating to form a hopper-bottom for said superheater cavity to facilitate cleaning of the same, said main furnace being disposed between said tube bank and said tube group; a superheater including a first section and a second section, said first section having a first pair of vertically disposed headers consisting of an inlet header and an associated header, said inlet header having a diaphragm means dividing the same into an upper and lower chamber, a plurality of U-shaped horizontally extending tubes connecting said upper and lower chambers of said inlet header with said associated header for establishing a steam path flowing from the upper chamber of said inlet header to said associated header and thence from said associated header to said lower chamber of said inlet header, said U-shaped tubes being disposed in the hot zone of said superheater cavity whereby said steam flowing therethrough is superheated to an intermediate temperature; said second section including a second pair of vertically disposed headers including an outlet header and an associated header, said outlet header having a diaphragm means dividing the same into an upper and lower chamber, a plurality of U-shaped, horizontally extending tubes connecting said outlet header chambers to said associated header for establishing a steam path flowing from said lower chamber of said outlet header to said second associated header and thence from said latter associated header to said upper chamber of said outlet header, said latter U-shaped tubes being disposed in said cooler zone of said superheater cavity, and a relatively large diameter connecting tube connecting said lower inlet header chamber to said lower outlet header chamber so that said intermediate superheated steam generated in said first section flows to said second section to be highly heated therein; said auxiliary furnace being disposed adjoining the hot zone of said superheater cavity so that the heating gases flowing therefrom is utilized to control the superheat of said steam.

12. A marine boiler comprising of a setting having a main furnace cavity; an auxiliary furnace cavity; a gas convection pass associated with said auxiliary furnace cavity and disposed between said furnace cavities, said convection pass including a hot gas zone and a cooler gas zone; means for independently firing each of said furnace cavities; an upper steam and water drum; a laterally offset lower water drum; a bank of inclined steam generating tubes connecting said upper and lower drums; a pair of smaller spaced water headers arranged below said upper drum; a spaced group of vertically arranged water tubes connecting the upper drum to each of said lower pair of water headers, said spaced group of tubes forming therebetween a superheater cavity, said pair of spaced water headers enabling said superheater cavity to be extended

to a maximum extent and said spaced water headers cooperating to form a hopper-bottom for said superheater cavity to facilitate cleaning of the same, said main furnace being disposed between said tube bank and said tube group; a superheater including a first section and a second section, said first section having a first pair of vertically disposed headers consisting of an inlet header and an associated header, said inlet header having a diaphragm means dividing the same into an upper and lower chamber, a plurality of U-shaped horizontally extending tubes connecting said upper and lower chambers of said inlet header with said associated header for establishing a steam path flowing from the upper chamber of said inlet header to said associated header in a counter flow heat transfer relationship to the gas flow and thence from said associated header to said lower chamber of said inlet header parallel flow heat transfer relationship to the gas flow, said U-shaped tubes being disposed in the hot zone of said superheater cavity whereby said steam flowing therethrough is superheated to an intermediate temperature, said second section including a second pair of vertically disposed headers including an outlet header and an associated header, said outlet header having a diaphragm means dividing the same into an upper and lower chamber, a plurality of U-shaped, horizontally extending tubes connecting said outlet header chambers to said associated header for establishing a steam path flowing from said lower chamber of said outlet header to said second associated header that is generally in a counter-flow heat transfer relationship to the gas flow and thence from said latter associated header to said upper chamber of said outlet header in a generally parallel flow heat transfer relationship to the gas flow, said latter U-shaped tubes being disposed in said cooler zone of said superheater cavity, and a relatively large diameter connecting tube connecting said lower inlet header chamber to said lower outlet header chamber so that said intermediate superheated steam generated in said first section flows to said second section to be highly heated therein; said auxiliary furnace being disposed adjoining the hot zone of said superheater cavity so that the heating gases flowing therefrom pass over said superheater whereby the relative heating gas flow to steam flow is such that the steam is highly superheated while the superheater tube temperatures are maintained below their high temperature corrosion limit.

13. A marine boiler consisting of a setting having a main furnace cavity; an auxiliary furnace cavity; a gas convection pass associated with said auxiliary cavity disposed between said furnace cavities, said convection pass including a hot gas zone and a relatively cooler gas zone; means for independently firing each of said furnace cavities; an upper steam and water drum; a laterally offset lower water drum; a bank of inclined steam generating tubes connecting said upper and lower drums; a pair of smaller spaced water headers arranged below said upper drum; a spaced group of vertically arranged water tubes connecting the upper drum to each of said lower pair of water headers, said spaced group of tubes forming therebetween a superheater cavity, said pair of spaced water headers enabling said superheater cavity to be extended to a maximum extent and said spaced water headers cooperating to form a hopper-bottom for said superheater cavity to facilitate cleaning of the same, said main furnace being disposed between said tube bank and said tube group; a superheater including a first section and a second section, said first section having a first pair of vertically disposed headers consisting of an inlet header and an associated header, said headers each having a diaphragm means dividing the same into a plurality of chambers, a plurality of U-shaped horizontally extending tubes connecting the chambers of said headers for establishing portions having alternating parallel and counter-flow heat transfer steam flow paths between said first pair of headers, said U-shaped tubes being disposed in the

hot zone of said superheater cavity whereby said steam is superheated therein to an intermediate temperature, and a second pair of vertically disposed headers including an outlet header and an associated header, said latter headers each having a diaphragm means dividing the same into a plurality of chambers, a plurality of U-shaped, horizontally extending tubes connecting the chambers of said last mentioned headers for establishing serially connected alternating parallel and counter flow heat transfer steam flow paths between said second pair of headers, said latter U-shaped tubes being disposed in said cooler zone of said superheater cavity, and a plurality of small diameter cross-over tube means connecting said first section to said second section for directing said intermediate superheated steam flow from said first superheater section to said second section whereby said intermediate superheated steam is highly heated in the latter section; said auxiliary furnace being disposed adjoining the hot zone of said superheater cavity so that the heating gases flowing therefrom are utilized to control the superheat temperatures of said steam.

14. The invention as defined in claim 13 wherein said small diameter cross-over tubes consist of a plurality of U-shape tubes horizontally disposed in the convection gas pass whereby said cross-over tubes function as additional superheating tubes.

15. A marine boiler comprising of a setting having a main furnace cavity; an auxiliary furnace cavity; a gas convection pass associated with said auxiliary furnace cavity and disposed between said furnace cavities, said convection pass including a hot gas zone and a relatively cooler gas zone; means for independently firing each of said furnace cavities; an upper steam and water drum; a laterally offset lower water drum; a bank of inclined steam generating tubes connecting said upper and lower drums; a pair of smaller spaced water headers arranged below said upper drum; a spaced group of vertically arranged water tubes connecting the upper drum to each of said lower pair of water headers, said spaced group of tubes forming therebetween a superheater cavity, said pair of spaced water headers enabling said superheater cavity to be extended to a maximum extent and said spaced water headers cooperating to form a hopper-bottom for said superheater cavity to facilitate cleaning of the same, said main furnace being disposed between said tube bank and said tube group; a superheater including a first section and a second section, said first section having a first pair of juxtaposed vertically disposed headers consisting of an inlet header and an associated header, said headers each having a diaphragm means dividing the same into an upper and lower chamber, a plurality of U-shaped horizontally extending tubes connecting said upper and lower chambers of said headers for establishing a serially connected alternating parallel and counter flow heat transfer steam path relative to said gas flow, said steam flowing from the lower chamber of said inlet header to the lower chamber of said associated header, thence from said lower chamber of the associated header to said upper chamber of said inlet header and then from said upper chamber of inlet header to the upper chamber of said associated header, said U-shaped tubes being disposed in the hot zone of said superheater cavity whereby said steam flowing therethrough is superheated to an intermediate temperature, said second section including a second pair of juxtaposed vertically disposed headers including an outlet header and an associated header, each of said second pair of headers having a diaphragm means dividing the same into upper and lower chambers, a plurality of U-shaped, horizontally extending tubes connecting the upper and lower chambers of said second pair of headers for establishing serially connected alternating parallel counter flow heat transfer steam path relative to said gas flow, said steam flowing from the upper chamber of said second mentioned associated header to the upper chamber of said outlet header,

thence from said upper outlet header chamber to the lower chamber of said latter associated header and then from said latter lower chamber to the lower chamber of said outlet header, said latter U-shaped tubes being disposed in said cooler zone of said superheater cavity, and a plurality of small diameter cross-over tubes connecting the upper chambers of the associated headers of each section, so that said intermediate heated steam generated in said first section flows to said second section to be highly heated therein; said auxiliary furnace being disposed adjoining the hot zone of said superheater cavity so that the heating gases flowing therefrom is utilized to highly superheat said steam.

16. For use in a marine boiler having a limited pre-determinate effective superheater heat absorption space in a gas convection pass having a hot zone and a relatively cooler zone, the improvement of a superheater having maximum heat absorption surfaces adapted to be positioned in said limited effective heat absorption space comprising a first superheater section including a first pair of headers having a plurality of nested U-shaped tubes connecting said headers for directing a steam flow between said headers, said tubes extending across the hot zone of said space; means for controlling the direction and velocity of the steams flowing in said tubes between said headers whereby said steam is directed in alternating parallel and counter-flow heat transfer passes relative to the gas flow whereby said steam is superheated to an intermediate temperature; a second superheater section including a second pair of headers having a plurality of nested U-shaped tubes connecting the same for directing a steam flow therebetween, said latter mentioned U-shaped tubes being disposed in the cooler zone of said space; means controlling the direction and velocity of the steam flow through said tubes connecting said second pair of headers whereby said steam is directed in an alternating parallel and counter flow heat transfer steam flow relative to said gas flow and means connecting said first and second sections in series whereby the intermediate superheater steams generated in said first section is highly superheated in said second section.

17. For use in a marine boiler having a limited pre-determinate effective superheater heat absorption chamber in a gas convection pass, the improvement of a heat absorption chamber having adjacent progressively decreasing gas temperature zones, a superheater having maximum heat absorption surfaces adapted to be positioned in said limited effective heat absorption chamber comprising a first superheater section including a first pair of headers having a plurality of nested U-shaped tubes connecting said headers for directing steam flow between said headers, said tubes extending across the hottest portion of said chamber, means for controlling the direction and velocity of the steams flowing in said tubes between said pair of headers whereby said steam flows therethrough in alternating parallel and counter-flow heat transfer passes relative to the gas flow for superheating the steam therein to an intermediate superheat temperature and a second superheater section including a second pair of headers having a plurality of nested U-shaped tubes connecting the same for directing a steam flow therebetween, said latter mentioned U-shaped tubes being disposed in a cooler portion of said chamber, means controlling the direction and velocity of the steam flow through said tubes connecting said second pair of headers whereby said steam is directed in an alternating parallel and counter-flow heat transfer relative to said gas flow and means connecting said first and second sections in series whereby the intermediate superheater steams generated in said first section are highly superheated in said section in a manner whereby metal temperatures of the

superheater parts are maintained below their high temperature corrosive limit, said velocity of the steam in the second section being greater than that in said first section to facilitate maintenance of tube temperatures in said second section.

18. A marine boiler consisting of a setting, an upper steam and water drum disposed centrally of said setting, a lower water drum disposed laterally of said upper drum, a bank of inclined steam generating tubes connecting said upper drum and laterally disposed lower drum, a pair of transversely spaced water headers positioned below and parallel to said upper drum, means for bottom supporting said spaced water headers, transversely spaced groups of vertically arranged screen tubes connecting said spaced water headers to said upper drum and forming therebetween a vertically elongated superheater cavity, refractory means cooperating with said pair of spaced water headers to define a hopper bottom for said superheater cavity having its lower end positioned between said spaced water headers, means forming an access opening for said hopper bottom between said spaced water headers, a main furnace chamber between said inclined tube bank and one of said groups of vertically arranged screen tubes, means for firing said main furnace, a steam superheater having a multiplicity of horizontally arranged tubes disposed in and extending substantially

throughout the height of said superheater cavity between said groups of vertically arranged screen tubes, an auxiliary furnace chamber laterally adjoining the outer side of said superheater tubes, said spaced water headers being arranged at approximately the same level as the bottoms of said main and auxiliary furnace chambers, means for independently firing said auxiliary furnace chamber, and a single heating gas outlet flue at the outer side of said inclined tube bank and arranged so that all of the heating gases produced in the main furnace are discharged directly to the flue after flowing over said inclined tube bank and the heating gases from said auxiliary furnace chamber are discharged to said outlet flue only after flowing over said superheater, through the main furnace chamber and across said inclined tube bank.
